UNITED STATES PATENT OFFICE.

EDMUND HUDSON, OF TEMPLETON, MASSACHUSETTS.

HYDROCARBON-ENGINE.

No. 864,844.

Specification of Letters Patent.

Patented Sept. 3, 1907.

Application filed July 28, 1904. Serial No. 218,565.

To all whom it may concern:

Be it known that I, EDMUND HUDSON, a citizen of the United States, and a resident of Templeton, in the county of Worcester and State of Massachusetts, have 5 invented certain new and useful Improvements in Hydrocarbon-Engines, of which the following is a specification.

The invention relates to engines of the hydrocarbon type commonly called gas engines and more particularly to the particular class of this sort in which a liquid hydrocarbon is injected into an air current to form the proper explosive mixture which when ignited will drive the piston of the engine.

The device hereinafter described is particularly 15 well adapted for the use of the heavier oils, as, for instance, kerosene.

The objects of my invention are to simplify as far as possible a hydrocarbon motor by discarding present methods of carbureting and to produce a two cycle 20 motor in which it is possible to use kerosene or other of the heavy and safe forms of petroleum.

A still further object is to provide a means of positively injecting the liquid fuel into the explosion chamber of the motor at predetermined intervals.

25 It is also an object to control with absolute precision the injection of said fluid and the quantity used for each charge of explosive mixture.

A still further object is to so inject and control a liquid fuel as to absolutely preclude explosions in the 30 crank case of a motor of the two cycle type, where the air is used and the explosive mixture is compressed in the crank case.

It is well known that in motors of the two cycle type 35 explosions often occur in the crank case of the motor, as a result of the sudden throttling of the motor, which permits the burning vapor which is under compression in the cylinder to find a vent through the intake passage when it is uncovered by the piston, and it is one of the objects of the present invention to absolutely 40 prevent back firing of the charges to the crank case.

An important feature and object of the invention is an arrangement by which a constant head or pressure of liquid fuel is maintained at the injection nozzle, and its flow to the combustion chamber automatically 45 controlled.

Referring to the drawings—Figure 1 is a view in elevation showing the main parts of the motor and with parts broken away to show construction. Fig. 2 is a view similar to that in Fig. 1 looking from the right of 50 said Fig. 1. Fig. 3 is a detail horizontal sectional view through the injecting apparatus and appurtenant parts. Fig. 4 is a detail view of the controlling mechanism for the nozzle.

Referring to the drawings the numeral 1 denotes the cylinder of an engine provided with a suitable crank 55 case 2, crank shaft 3 and fly wheel 4. Within the engine cylinder, as is usual, there is mounted a reciprocating piston 5 connected with the crank shaft 3 with suitable connection rod 6. The engine herein shown is of the type known as the two cycle motor, and its 60 cylinder is provided with suitable inlet and exhaust ports as indicated respectively at 7 and 8.

When the piston is at the upper limit of its play it uncovers an air port 9 and upon its downward movement it of course compresses the air in the crank case 65 2 and forcibly drives it through a passage 10 as soon as the inlet port 7 is uncovered by the downward movement of the piston 5. This piston has the usual deflector 11 upon its head, so arranged as to deflect the currents of explosive mixture as they impinge against it and thus prevent their escape through the exhaust port 8.

The several parts above described have not been shown in detail, as they are well-known features of all 70 motors of the class defined, and no means are specifically shown in the accompanying drawings for igniting the charges of explosive mixtures as they are compressed in the cylinder, it being understood that any well-known form of igniter might be used.

Arranged adjacent to the passage 10 and the inlet 75 port 7 is an injecting apparatus shown in detail in Fig. 3. This consists essentially of a supply 12 through which the hydrocarbon is introduced, and a pump piston 13 for inducing the necessary flow of oil at predetermined instants through an injecting nozzle 14.

The several parts of the injecting apparatus are mounted in a suitable casing 15 secured to the cylinder in any suitable manner, with the injection nozzle 14 located to throw its hydrocarbon across the upper end of the chamber 10 adjacent to the inlet opening 7. As 80 a matter of fact, the nozzle is so arranged as to project its oil directly through the opening 7 and against the deflector 11. The pump piston 13 is mounted to slide in a tube 16 and is normally held at the outer limit of its play by a spring 17. This piston bears at its outer 85 end a roll or anti-friction device 18 which at predetermined instant comes into contact with a movable cam or actuator 19 borne in the fly wheel 4. This projection 19 is mounted to move in the fly wheel and is controlled as to its position by levers 20—21, the latter 90 of which is weighted and normally held against a stop 22 by a spring 23. This system of levers, the latter of which is weighted as indicated at 24, forms a governing device for controlling the action of the piston 13. Under normal conditions the cam 19 comes into contact 95 with the roll 18 upon each revolution of the fly wheel,

but if the speed of the fly wheel is abnormally increased the weighted lever 21 reacts against the spring 23 and carries the cam 19 out of registering position with the roll 18, thus permitting the piston 13 to lose its 5 strokes until the normal speed of the engine is again attained.

In the opposite end of the tube 16 from that occupied by the piston 13 is a valve 25 having a somewhat peculiar construction and function. This valve 10 consists of a main body part 26 normally held forward by a comparatively stiff spring 27 and filling the entire opening of the tube 16. In the inner end of the valve body 26 is arranged a puppet valve 28, through which the oil introduced to the inlet 12 will readily flow upon the 15 suction stroke of the piston 13. It is to be noted that the capacity of the tube 16 between the valve 25 and piston 13 is somewhat greater than the capacity of the injection nozzle 14, which extends therefrom, and the purpose of the movable valve body 26 is to maintain a 20 forced pressure upon the hydrocarbon in the tube 16 and always insure a complete filling of the injection nozzle tube, thus precluding any possibility of drawing flame or gas back through the injection nozzle.

The injection nozzle 14 is of peculiar construction 25 and consists of an inner tube 29, the outer end of which is perforated as at 30. About this tube is arranged an inclosing and controlling casing or tube 31. This also has perforations which under normal conditions are out 30 of registering position with the orifices of the inner tube 29 and effectually close said openings and prevent the passage of oil. The outer casing 31 is connected with a crank arm 32, slotted as at 33 and connected through a rod 34 with a pin 35 secured to the piston 13. This connection is for the purpose of opening the orifices of the 35 injection nozzle at a predetermined instant during the stroke of the pump piston 13. To secure a means of adjusting and varying the relative amount of hydrocarbon passed through the opening of the nozzle a rod 36 is connected to the rod 34 and is controlled by a handle 40 37 through a crank arm 38, the arrangement being such that the throw of the crank arm 32 may be varied by the position of the end of the rod 34 with relation to the slot 33.

In order to provide for the ready starting of the 45 engine with one of the lighter oils a stop cock 39 is introduced in the inlet 12 and a draw off cock 40 is used to withdraw the oil from the tube 16. When this stop cock 40 is closed a light oil may be introduced through an opening 41 to fill the tube 16, and the stop cock 39 50 may then be opened to permit the flow of the heavier oil as the engine is started.

Having described the several detailed parts of the mechanism for carrying out my invention, its operation can now be more specifically defined.

55 It is to be observed that the injection of hydrocarbon through the nozzle is practically instantaneous and is accurately controlled by the movement of the pump piston 13. This pump piston in turn is automatically controlled in its movements by the self-regulating governor 60 which actuates the cam which engages and moves the piston on its pumping stroke. By the arrangement described the pump performs its work in the shortest possible time, and the injection of the liquid into the explosion chamber is so graduated as to prevent its entrance 65 until after a quantity of pure air from the crank

case has begun to enter the explosion chamber and cylinder. That is, the injection of the liquid is delayed until the piston on its downward stroke has partially uncovered the orifice of the inlet port. The object and result of this control of the instant of injection of a fluid 70 is to first scavenge the explosion chamber and cylinder with a quantity of pure air, which being forcibly driven from the crank case encounters the burned gases produced by the previous explosion and dissipates them. Thereupon there is introduced into the explosion 75 chamber between the burned gases and the fresh charge a slight cushion of pure air, the result of which is to prevent the mixture of the petroleum vapor with the burned gases and to absolutely preclude the escape through the exhaust port of the active petroleum vapor prior to the 80 covering of the exhaust port by the return movement of the piston.

Whenever the governing device by its operation permits the petroleum pump to become inactive, the explosion chamber receives only pure air, which completely scavenges said chamber and also tends to cool it, there being no explosions until the petrol pump is again actuated. Of course, when the pump is temporarily out of operation the nozzle of the injection tube is completely closed and then there is no escape of oils 85 unless the pump is positively actuated, and upon its actuation and the uncovering of the orifices of the nozzle the oil is introduced instantaneously and with absolute precision as to the instant of operation of the several parts of the mechanism.

The injection of oil through the nozzle is always so timed as to be thrown against the deflector of the piston, which in the operation of the motor is heated to extremely high temperature and thus volatilizes the mixture introduced.

Obviously various changes might be made in the details of the several parts without materially departing from the invention, and various forms of pumping apparatus and connections therefor might be used, the particular object being to always introduce a charge of oil at 105 a known instant and to prevent all possibility of back firing into the crank case of the engine and into the inlet tubes for the fuel.

What I claim as my invention and desire to secure by Letters Patent is:

1. In combination in a hydrocarbon motor having a combustion chamber and an air compression chamber, an air passage intermediate the air compression chamber and combustion chamber, a piston arranged to control the passage of air intermediate said chambers, a crank shaft, a hydrocarbon pump, having means for maintaining an oil pressure in the pump chamber irrespective of the position of its piston and means intermediate the crank shaft and pump for operating said pump piston, and an opening and closing injection nozzle operatively arranged with 115 reference to the pump and combustion chamber.

2. In combination in a hydrocarbon motor having a combustion chamber and an air compression chamber, an air passage intermediate the air compression chamber and combustion chamber, a piston arranged to control the 120 passage of air intermediate said chambers, a crank shaft, a hydrocarbon pump, having means for constantly maintaining an oil pressure in advance of the pump piston and means intermediate the crank shaft and pump for operating the pump piston, an injection nozzle operatively arranged with reference to the pump and combustion chamber, and means for varying the amount of hydrocarbon passed through said injection nozzle and the instant of its passage.

3. In combination in a hydrocarbon motor having a combustion chamber and an air compression chamber and connections intermediate said chambers, a hydrocarbon tube, a pump piston arranged to reciprocate therein, means for reciprocating said piston, an injection nozzle appurtenant to said pump and adapted to discharge into the combustion chamber, a resilient plug arranged within the hydrocarbon tube, and a valve carried by said resilient plug.
- 10 4. In combination in a hydrocarbon motor having a combustion chamber, a hydrocarbon injector arranged appurtenant thereto and comprising a normally closed nozzle, a hydrocarbon tube appurtenant to said nozzle, a piston arranged within said tube, a resilient plug normally 15 resisting the working stroke of said piston, a valve borne by the plug, and connections intermediate the piston and nozzle whereby said nozzle is opened at predetermined instants with reference to the working stroke of the former.
- 15 5. In combination in a hydrocarbon motor having a combustion chamber and an air compressing means appurtenant thereto, a piston arranged to control the flow of fluid from the air compressor to the combustion chamber, a hydrocarbon pump having an oil chamber, automatic 20 means for maintaining an oil pressure in said oil chamber and a piston with means for periodically actuating the same to raise the pressure within the oil chamber and automatic means for releasing the oil into the combustion chamber in varying quantities.
- 25 6. The combination in a hydrocarbon motor including a combustion chamber, a compression chamber, piston, crank shaft and fly wheel of an injecting device, including a plunger, a roll carried in the end of said plunger, a movable projection borne in the fly wheel and adapted to engage said roller, and automatic means for varying the position of said projection.
- 30 7. In combination in a hydrocarbon motor having a combustion chamber and a hydrocarbon injector appurtenant thereto, a pump piston, a nozzle having two relatively movable parts arranged to control the opening and closing 35 of the nozzle, connections intermediate one of said parts and the pump piston for automatically controlling the opening and closing movements of the nozzle at predetermined instants with reference to the movements of the pump piston, and manually operated means for varying the relative operation of said parts.
